UNITED STATES PATENT OFFICE.

LEO MORSE, OF NEW YORK, N. Y.

DESIGN FOR A TOY RATTLE.

Application filed May 29, 1924. Serial No. 9,734. Term of patent 7 years.

To all whom it may concern:

Be it known that I, LEO MORSE, a citizen of the United States, residing in the city, county, and State of New York, have invented a new, original, and ornamental Design for Toy Rattles, of which the following is a specification, reference being had to the accompanying drawing, forming a part thereof, and of which—

Figure 1 is a front elevation and Fig. 2 is a side elevation of a toy rattle showing my new design.

I claim:

The ornamental design for a toy rattle as shown.

LEO MORSE.
